PARALLEL MOTION FOR LOOMS

Leonard M. Rogers, Mendon, Mass., assignor to
Draper Corporation, Hopedale, Mass., a corpora-
tion of Maine

Application January 12, 1937, Serial No. 120,257

5 Claims. (Cl. 139—150)

The present invention pertains to the shuttle picking mechanisms of fly shuttle looms and has more particular reference to the devices for supporting and guiding the picker stick of such 5 mechanisms.

Looms of the type to which my invention pertains commonly include a parallel, so-called, a curved shoe rocking on the parallel, a picker stick fixed to and rocking with the shoe, means 10 engaging the picker stick for imparting operative movement thereto, and thrust means carried by the parallel for receiving the inward thrust of the lower end of the picker stick. Prior to the present invention, such thrust means as used commercially consisted of a parallel plug, so-called, attached to the parallel and provided with a rounded nose which was engaged by a wear tongue on the picker stick. Inasmuch as the picker stick has a vertical movement relative to the parallel plug, such plugs and the wear tongues wear out 15 rapidly and must be replaced frequently.

It has been proposed to eliminate the aforementioned parallel plug and substitute therefor a roller journaled on a pin carried by the parallel. Such proposed construction has not been satisfactory and has not been used commercially to any 20 great extent, partly because of the difficulty of lubricating the bearing pin and because of the inability of such a pin to withstand the repeated 25 blows of the picker stick.

The principal object of the present invention is to provide in a loom, a parallel, shoe, picker stick, and wear tongue as aforesaid and a parallel plug having a roller journaled in an open-sided bearing 30 therein and exposed through the bearing for engagement by the wear tongue, to thereby provide a novel and efficient anti-friction bearing for the picker stick.

The foregoing and other objects of the invention are accomplished in the construction illustrated on the accompanying drawing, of which:

Fig. 1 is a front elevation, partly in section, of mechanism comprising the preferred embodiment of the invention;

Fig. 2 is a plan view of a part of the mechanism of Fig. 1, to a larger scale; and

Fig. 3 is a detail view in perspective of certain parts shown on Figs. 1 and 2.

The mechanism shown on the drawing is applied to a fly shuttle loom which is generally of conventional construction and the drawing accordingly shows only a part of a loom side 1 and such part of the shuttle picking mechanism as is necessary to an understanding of the present 55 invention. It will be understood that the loom

side 1 is at the left hand side of the loom and that the shuttle picking mechanism shown is the left hand mechanism, there being another picking mechanism, not shown, at the other side of the loom.

The shuttle picking mechanism includes a support 2, commonly known in the art as a parallel, which is fixed to the lay rocker shaft 3 and which extends outwardly of the loom from the loom side 1. The parallel has an upper surface 4, preferably flat, on which a curved shoe 5 rests. The shoe 5 rocks on the parallel and may be guided in its movements by a guide fin 6 which projects upwardly from the parallel into a slot in the shoe. The parallel is provided with an opening 7 beneath the shoe 5.

A picker stick 8 is fixed to the shoe 5 to rock therewith. To this end the picker stick may extend through the shoe and be secured thereto by a bolt 9 which passes through the shoe, picker stick and the end of a strap 10. The lower end of the picker stick projects downwardly through the opening 7 and the strap 10 extends around the lower end of the picker stick and to a spring-actuated drum 11. The upper end of the picker stick is moved inwardly of the loom, which is toward the right on Fig. 1, by a conventional lug strap, not shown, and the drum 11 and strap 10 return the upper end of the picker stick outwardly, or toward the left on Fig. 1.

Since the lug strap and strap 10 both tend to pull the lower end of the picker stick inwardly of the loom, means is provided for receiving the thrust of the lower end of the picker stick and thereby holding the stick against inward movement. Such holding means must accommodate the vertical movement of the lower end of the picker stick which results from the rocking of the curved shoe 5 on the flat surface 4. To this end, a wear tongue 12 is fixed on the inner edge of the lower end of the picker stick, as by a setscrew 13, and a member 14 is fixed in the parallel 2 at the inner end of the opening 7. The member 14, although of novel construction, is herein-after called a parallel plug, that being the technical name of prior devices for receiving the thrust of the lower end of the picker stick.

The particular parallel plug 14 shown on the drawing consists of a relatively flat elongated body having a cylindrical anti-friction roller 15 journaled therein. The body of this parallel plug is tapered toward its inner end so that it may be wedged into a horizontal pocket in the parallel 2 with the outer end of the plug projecting into the opening 7. The parallel plug is pro-

vided with a head 16 extending transversely across the outer end thereof. A bearing 17 extends through the head 16 and the roller 15 is journalled directly in this bearing.

5 The bearing 17 extends entirely through the parallel plug from the front to the rear edge thereof, but the side of the bearing which is at the outer end of the plug is open, to expose one side of the roller 15. The exposed side of the roller 15 is directly engaged by the wear tongue 12. The bearing 17 may be formed by first forming the parallel plug with a larger head 16 than is shown, then drilling or otherwise forming a completely cylindrical bearing in the head, and 10 then removing the outer or left-hand portion of the head to thus open one side of the bearing. I prefer to remove as much of the head as is necessary to expose the roller, leaving at least part of the bearing extending around more than half 15 of the circumference of the roller. The roller is thus held in the bearing and cannot drop out while the loom is in operation.

The diameter of the bearing 17 is just enough 20 larger than the diameter of the roller 15 to permit the roller to rotate freely in the bearing without appreciable lost motion. Since no part of the head 16 projects outwardly beyond the exposed side of the roller, the thrust of the lower end of the picker stick is received by the roller 25 and transmitted through the body of the plug 14 to the parallel 2. I have thus provided an anti-friction bearing which is sufficiently strong to withstand the repeated shocks to which it is subjected. Furthermore, the bearing and the 30 external surface of the roller are easy to lubricate because lubricant applied to the roller will be carried to the bearing surface by rotation or oscillation of the roller.

35 The parallel plug 14 as above described is detachably mounted in the parallel whereby it may be removed and replaced if so desired. Such plug may be made of proper size to fit existing parallels. The parallel plug therefore constitutes a marketable article of manufacture which I desire to claim as such.

Having fully disclosed the preferred embodiment of my invention, I claim:

1. In a loom the combination of a parallel 40 having an opening therein, a curved shoe rocking on said parallel, a picker stick fixed to said shoe, the lower end of said picker stick projecting downwardly through said opening, a wear tongue on the inner edge of said picker stick at the lower end thereof, and a plug fixed to said parallel and 45 projecting into said opening to receive inward thrust of the lower end of said picker stick, said plug comprising a body having an open sided bearing extending transversely thereof at its outer end and a cylindrical roller journalled di-

rectly in said bearing and exposed through the open side thereof, the exposed side of said roller being engaged by said wear tongue.

2. In a loom the combination of a parallel having an opening therein, a curved shoe rocking on 5 said parallel over said opening, a picker stick fixed to said shoe, the lower end of said picker stick projecting downwardly through said opening a wear tongue on the inner edge of said picker stick at the lower end thereof, and a plug 10 detachably fixed to said parallel at the inner end of said opening, said plug comprising a body having a head at its outer end and a cylindrical roller journalled in a bearing in said head and extending transversely of said picker stick, said 15 bearing being open at one side to expose one side of said roller and the exposed portion of the roller being in engagement with said wear tongue to receive the inward thrust of the lower end of said picker stick, at least part of said bearing 20 extending around more than half of the circumference of said roller to thereby retain the latter in the bearing.

3. As an article of manufacture, a parallel plug 25 for receiving the thrust of the lower end of a picker stick, said plug comprising a body adapted to be attached to a loom parallel, said body having a bearing extending transversely through one end thereof, one side of said bearing being open, and a cylindrical roller journalled directly in 30 said bearing, one side of said roller being exposed through said opening for the purpose described.

4. As an article of manufacture, a parallel 35 plug for receiving the thrust of the lower end of a picker stick, said plug comprising a body adapted to be attached to a loom parallel, said body having an open-sided bearing extending transversely through one end thereof, and a cylindrical roller journalled directly in said bearing, one side of said roller being exposed through 40 the open side of said bearing, and at least a part of said bearing extending around more than half of the circumference of said roller to thereby retain the latter in the bearing.

5. As an article of manufacture, a parallel plug 45 for receiving the thrust of the lower end of a picker stick, said plug comprising a relatively flat elongated body adapted to be attached to a loom parallel, said body having a bearing extending 50 transversely through one end thereof, the side of said bearing at the end of said body being open, and a cylindrical roller journalled directly in 55 said bearing and exposed through the open side of the latter, said bearing throughout its length extending around more than half of the circumference of said roller to thereby retain the latter in the bearing.

LEONARD M. ROGERS.
